UNITED STATES PATENT OFFICE

JOHN HOLTZMAN, OF NEW YORK, N. Y., ASSIGNOR OF ONE-HALF TO C. JAMES COTTRELL,
OF NEW YORK, N. Y.

CIGARETTE CASE

Application filed December 16, 1929. Serial No. 414,274.

This invention relates to a device adapted to cover and maintain the shape of a cigarette carton, and to automatically eject cigarettes therefrom.

At the present time, the popular brands of cigarettes are vended in paper cartons of a standard size. When completely filled with cigarettes the paper carton satisfactorily protects its contents; but after the removal of one or two cigarettes, the remaining cigarettes become loose and the paper of the carton is insufficient to protect the cigarettes from being broken, smashed, and generally rendered unsatisfactory for smoking purposes. A number of devices have been produced for overcoming the above objections to the paper carton, but such devices have been found insufficient in that they do not enable the easy extraction of a cigarette from a carton.

It is an object of this invention to provide a device to maintain the shape of a cigarette carton, said device having means for automatically ejecting cigarettes from the carton.

A further object is the provision of a device adapted for use in combination with a carton of cigarettes for automatically ejecting cigarettes therefrom.

These and other objects are attained by the novel construction, combination and arrangement of parts hereinafter described and shown in the accompanying drawings, constituting a material part of this disclosure and in which:

Fig. 1 is a side elevational view of the device in combination with a carton of cigarettes.

Fig. 2 is an elevational sectional view of the device in a closed condition.

Fig. 3 is an elevational sectional view of the device in an open condition.

Fig. 4 is a sectional view taken on line 4-4 of Fig. 2.

Fig. 5 is a sectional view taken on line 5-5 of Fig. 2.

Fig. 6 is a side elevation in section of a modified form of the device in a closed condition.

Fig. 7 is a similar view showing the modi-

fied form of the device in an open condition.

Fig. 8 is a sectional view taken on line 8-8 of Fig. 6.

Fig. 9 is a sectional view taken on line 9-9 of Fig. 7.

Referring to Fig. 2 of the drawings, there is shown a wire frame member having vertical legs 10 and 11 connected by the horizontal portion 12, the legs 10 and 11 being in the form of loops and inserted between the outer paper layer 13 and the inner paper layer 14 of a carton containing cigarettes 15.

Attached to the horizontal wires 12 are the side walls 16 of a metal top 17, which has a tongue 18 engaging the under side of the rear portion of a cover 19, the latter being pivoted on a pin 20. Encircling the pin 20 is a coiled spring 20' having one extremity 21 engaging the under side of cover 19, and the other extremity 22 fixed to the projection 23 on a metal casing 24.

The bottom of the casing 24 has hinged thereto a cover 25 provided with a spring tongue 26 for resiliently gripping an end wall of the casing. Projecting upwardly from the cover 25 is a lug 27, which is adapted to pass through a hole in the bottom of the paper carton and engage one or more cigarettes in the carton. A flat spring 28 attached to the cover 25 presses against the bottom of the carton and normally urges the latter upwardly.

In operation, a portion of the top of the paper carton is removed and an aperture 29 is made in the bottom of the carton. The carton is then inserted in the casing 24 through the bottom thereof, the legs 10 and 11 being inserted between the outer paper layer 13 and the inner paper layer 14 of the carton, and the tongue 26 caused to frictionally grip a side wall of the casing to hold the cover 25 in place.

The pressure of spring 28 on the bottom of the carton causes the tongue 18 to engage the rear of the cover 19 and maintain the latter in a closed condition.

When a cigarette is desired, the top 17 is depressed against the action of spring 28 to relieve the pressure of tongue 18 on cover 19 and the coiled spring 20' then causes the cover 19 to open. Obviously, pressure on top

17 will move the carton of cigarettes downwardly, but one or two of the cigarettes are maintained in a raised position by contact with the lug 27, and when the cover 19 is open, these one or two cigarettes will stand out above the rest of the cigarettes in the carton so that they may be conveniently extracted.

In the modified form shown in Fig. 6, a wire frame member has a horizontal portion 32 connecting the looped vertical legs, 30 and 31, which are inserted between the inner paper layer 41 and the outer paper layer 40 of a carton of cigarettes. Attached to the horizontal portion 32 are the side walls 33 of a cover 34, in which is mounted a pin 35 having pivoted thereon the cover portion 38. The pin 35 is encircled by a spring having one end 36 engaging the inner surface of the cover 38, and the other end engaging the inner surface of the cover 34. The cover 38 is provided with lips 39 adapted to snap over the horizontal wires 32 to hold the cover in a closed condition.

The carton is carried in an inner casing 42 open at each end and having side walls 44 provided with protuberances 46 adapted to snap into the apertures 45 in the side walls of the outer casing 43, the latter having a boss 47 projecting upwardly from its bottom wall.

In operation, the paper cover of the carton is removed and an aperture is made in the bottom of the carton. The legs 30 and 31 are then inserted between the inner and outer layers of paper of the carton, after which the latter is placed in the inner casing so that the aperture in the bottom of the carton will substantially coincide with an aperture in the bottom of casing 42, the latter registering with the boss 47. When the inner casing is inserted in the outer casing 43 and the humps 46 enter the apertures 45, the cover 38 will remain in a closed condition as there is no pressure upon the legs 30. When a cigarette is desired, pressure is applied to the top 34 to force the carton and inner casing 42 downward against the action of spring 48 on the bottom of casing 43. As casing 42 moves downward, the humps 46 move out of the apertures 45 and are pressed inwardly by contact with the walls of casing 43. This action presses the legs 30 inwardly to release the cover 38. During the downward movement of the carton, the boss 47 has maintained one or more cigarettes in an elevated position in a manner similar to that described in connection with the form shown in Fig. 1. These cigarettes may be readily extracted from the carton as they stand out and above the other cigarettes in the carton.

From the above description it will be seen that I have provided a simple device by means of which a carton of cigarettes may be uncovered and simultaneously one or more

cigarettes may be automatically ejected therefrom.

The foregoing disclosure is to be regarded as descriptive and illustrative only, and not as restrictive or limitative of the invention, of which obviously an embodiment may be constructed including modifications without departing from the general scope herein indicated and denoted in the appended claims.

Having thus described my invention, what I claim as new and desire to secure by Letters Patent, is:

1. A covering device for cigarette cartons, comprising a wire frame member having legs insertable between the inner and outer paper layers of the carton, a plate attached to the frame member, a casing adapted to receive the carton and the member, a cover pivotally connected to the casing, resilient means normally urging the cover to an open position, a tongue on the plate engaging the cover to hold the latter closed, a spring attached to the bottom of the casing and adapted to engage the bottom of a carton contained therein, and a lug projecting upwardly from the bottom of the casing to eject a cigarette from the carton as the latter is moved downwardly.

2. In combination with a carton of cigarettes, said carton having an aperture in its bottom, a casing housing the carton, a spring in the bottom of the casing bearing against the bottom of the carton, and a lug projecting from the bottom of the casing through the aperture in the carton to eject a cigarette from the carton as the latter is moved downwardly.

3. In combination with a carton of cigarettes, said carton having an aperture in its bottom, a casing, resilient means in the casing normally urging the carton upwardly, a lug in the casing projecting upwardly through the aperture in the carton to eject a cigarette from the carton as the latter is moved downward, a cover for the carton, and means to raise the cover simultaneously with the ejecting of a cigarette.

4. In combination with a carton for cigarettes, a device comprising a frame insertable in the carton to maintain the shape of the latter, a plate fixed to the frame, a casing, a cover pivotally mounted on the casing, means to normally hold the cover open, and means on the plate to hold the cover closed, resilient means in the casing bearing against the bottom of the carton, and a lug projecting from the bottom of the casing upwardly through an aperture in the bottom of the carton to eject a cigarette from the carton as the latter is moved downwardly.

5. In combination with a carton of cigarettes, said carton having an aperture in its bottom, an open ended inner casing in which the carton is carried, said casing having an aperture coinciding with the aperture in the

carton, an outer casing receiving the inner casing, resilient means in the outer casing bearing against the bottom of the inner casing, and a lug projecting upwardly from the outer casing through the apertures.

5. In combination with a carton of cigarettes, a wire frame member inserted in the carton, a spring controlled cover for the member adapted to be released by squeezing the latter, an inner casing in which the carton is carried, said casing having an aperture in its bottom, an outer casing receiving the inner casing, said outer casing having apertures in its sides, said inner casing having protuberances from the sides adapted to enter the apertures in the outer casing, resilient means in the outer casing bearing against the bottom of the inner casing, and a lug in the outer casing projecting upwardly through the aperture in the inner casing.

6. In an article carrying device, an outer casing, a member slidably mounted in the casing, a cover hinged to the member, means for normally holding the cover open when the member is in a lowered position, and resilient means in the casing to maintain the member in a raised position.

7. In an article carrying device, an outer member, an inner member slidably mounted in the outer member, a normally open cover hinged to one of the members, resilient means normally maintaining the inner member in a raised position, and means on the inner member to maintain the cover closed when the inner member is in a raised position.

8. In an article carrying device, a pair of members, one of said members arranged to telescope within the other, spring means interposed between said members, a cover hinged to one of the members, and means actuated by telescoping action of the members against the tension of the spring to raise the cover and expose an article carried by the device.

9. In an article carrying device, a pair of members arranged to telescope one within the other, resilient means interposed between said members, a cover carried by one of the members, means carried by one of said members for ejecting an article from the device, and means actuated by telescoping action of the members against the action of the resilient means to raise the cover and simultaneously eject the article.

In testimony whereof, I affix my signature.
JOHN HOLTZMAN.
